UNITED STATES PATENT OFFICE.

GUST HALL, OF ST. FRANCES TOWNSHIP, ANOKA COUNTY, MINNESOTA.

COALING DEVICE FOR TRAINS IN MOTION.

1,105,271.

Specification of Letters Patent.

Patented July 28, 1914.

Application filed December 23, 1912. Serial No. 738,251.

To all whom it may concern:

Be it known that I, GUST HALL, a citizen of the United States, residing at St. Frances township, in the county of Anoka and State 5 of Minnesota, have invented a new and useful Coaling Device for Trains in Motion, of which the following is a specification.

My invention relates to devices for delivering heavy articles in general to trains 10 while they are in motion.

The primary object, however, is to enable railway trains to coal without stopping, since stopping does not only consume the time necessary to fill some coal into the 15 tender but also the considerable length of time it takes to start a heavy train, especially a freight train, again and get it into full speed after the coal is taken on; in some cases and localities such starting is very 20 difficult, if not impossible, without an extra engine rendering assistance.

In carrying out my invention I provide at each coaling station of a rail road a short side track, a coal-delivering carriage on the 25 side track and provided with a dumping bucket for delivering the coal quickly into the tender of the train. I also provide means whereby the approaching train engages and starts the carriage into motion 30 which is gradually increased until the tender gets in position for receiving the coal.

Another principal feature of the invention is to have the side track so diverging from 35 the railroad track that the coal-delivering carriage will thereby be separated from the tender at the proper time.

A third principal feature is to have the side track inclined toward the coal supply, 40 so that the emptied carriage will of its own weight return to the point where it is to be filled, and such returning movement of the carriage also operates to restore the train-operated mechanism to normal position 45 for the next train to operate it.

In the accompanying drawings,—Figure 1 is a top or plan view of a portion of a railroad track, a tender mostly in outlines, on the track, and my coaling device arranged

at one side of the track. Fig. 2 is a sectional view on the line *a—a* Fig. 1, showing my device in side elevation. Fig. 3 is an enlarged left hand end elevation of the device and the railroad track as shown in Fig. 1, but with some parts omitted and the tender shown as much clearer as the enlarged scale will permit. Fig. 4 is an enlarged rear elevation of the mechanism box 32, and the mechanism therein, shown in Fig. 2 as arranged in the ground below a platform 33, with the rear wall 32^a and the bearing block 36, shown in Fig. 5, removed. Fig. 5 is a right hand side elevation of the box and mechanism shown in Fig. 4, with the side wall 32^b omitted. Fig. 6 is an enlarged inside elevation of a fragment of the side of the tender over which the coal is delivered, showing catches by which the coal bucket is held in tilted position while it is discharging its contents. Fig. 7 is an enlarged portion of Fig. 3, showing more clearly and further improved the means by which the coal carriage is connected with the cable that moves it. Fig. 8 is a right hand side elevation of the parts shown in Fig. 7, with the carriage locked at the place where it is to be filled. Fig. 9 is similar to Fig. 8, but shows the carriage in the relative position it occupies at the time it leaves the place of supply. Fig. 10 is an enlarged portion of the plan view Fig. 1, showing more clearly how the coal bucket is locked by a mechanism operable by the tender when the latter is in a position to receive the coal. Fig. 11 is a portion of the mechanism shown in Figs. 8 and 9, showing how the stud 53 acts on the end portions of the fork when the carriage returns. Fig. 12 is an enlarged and further improved side elevation of the parts 63, 64, 65 in Fig. 2.

Referring to the drawings by reference numerals, 1 designates the ground and 2 the railroad track over which a train is to pass while supplying its tender with coal for the locomotive.

Suitably near one side of the track 2 is provided a side track, which in the present illustration is composed of two parallel in-

clined rails, 3, secured one higher than the other on a series of posts 4 fixed in the ground; 5 indicate blocks interposed between the posts and the rails, so as to create clearings between the two for the flanges of rail-wheels 6 to pass through. Said wheels rotate on studs 7 (best shown in Fig. 3) fixed in a skeleton frame 8, in which is trunnioned to tilt at 9 a scoop-shaped coal bucket 10, adapted to hold the usual quantity of coal taken at one time into a tender. The frame 8 is provided with two, preferably rearwardly inclined posts 11, having each in its top a rope sheave 12 and at the rear side a guide rod 13. On each of said guide rods slides a weight 14, which is attached to a rope 15, that is passed over the sheave and attached to the coal bucket 10, so as to return the latter to normal position as soon as it is emptied. The bucket is normally held in its upstanding position by a hook 16 fixed on it (best shown in Fig. 10) and engaging a catch 17, which is pivoted at 18 to the rear top bar of the frame 8 and operated by a rod 19 and a trip lever 20; the latter is fulcrumed at 21 on said frame and has its front end 20^x normally held by a spring 22 as far as possible to the side from which the train is expected to come, and while in said position the spring also holds the catch 17 engaged in the hook 16. The said front portion 20^x of the trip lever is guided to swing horizontally in the narrow portion of a V-shaped fork 23, whose lower tine is provided with one or more self-closing catches 24 (see Fig. 2) adapted to close automatically the opening between the tines and thereby prevent the escape of an arm 25 of the tender, after said arm has overtaken and partly entered into the fork, until the arm can advance farther and by pressing against the lever portion 20^x, so it swings into the space 26 of the fork, disengages the catch 17 from the hook 16 and permits the bucket to be tilted by the weight of the coal in it, as shown in dotted lines in Fig. 3. When the bucket reaches that position its horns 27 pass downward between and are caught by catches 28, (best shown in Fig. 6) which are pivoted at 29 to the tender 29^x and are normally held by a spring 30 against the stops 31; said catches thus hold the bucket tilted while the contents are fully discharged into the tender, so that the weights 14 can not raise the bucket when it is partly emptied and thus not held down by the coal. After the bucket is emptied it is entirely disengaged and separated from the tender by the lateral motion of the frame 8 caused by the laterally diverging of the portion 3^x of the side track; said lateral motion also removing the upper arm 25 of the tender from the fork 23. The carriage 8 being thus set free returns by its own weight down the inclined side track to the point where it started from

when the train engaged it, and while it thus returns it restores to normal position the mechanism by which the train engaged and moved it. Said mechanism will now be described.

A box or inclosure 32 is preferably concealed in the ground and covered by a platform 33. The latter is provided with two parallel slots 34, and holes 35, and upstanding bearing blocks 36, 37. In the box is mounted to rotate about a horizontal axis a spiral-grooved cone 38, and parallel to said axis are fixed two rods 39 in the lower part of the box, and two similar rods 40 in the bearing blocks upon the platform. On said rods is slidably mounted a skeleton frame 41, which is moved on the rods by one or more arms 42, which are pivoted each with one end to the frame and at the other end provided with a roller 43 which engages in the spiral groove of the cone. On said four rods rotate and slide four rope-guiding sheaves 44, each of which is engaged by the slideable frame 41, so that the rope, or cable, 43^x, which is taken one or more turns around the cone, and is guided by said sheaves, is bound to remain in the spiral groove during the rotation of the cone. Said cable 43^x is endless and passed horizontally from the top of the upper sheaves 44, and upwardly over sheaves 45, 46 on a post 50, and over sheaves 47, 48 on a higher post 51, and thence in the inclined position of the track 3, thus forming an upper run 42^x, on which is fixed a catch 52 (best shown in Figs. 7, 8 and 9), engaging permanently a stud 53 fixed in the carriage frame 8 and operated in a manner presently to be fully described.

Fulcrumed on the post 50 is an L-shaped lever 54, having its short arm provided with a rope sheave 55 engaging the cable, and on the longer arm is adjustably mounted a weight 56 which tends at all times to hold the cable properly stretched as it moves from the small to the large end of the cone, or from the large to the small end. The stretching device just described also takes up the slack resulting from wear and tear of the cable; and, finally, it aids in locking and unlocking the carriage, as will be seen in that part of the description.

The cone 38 has its large end provided with two peripheral grooves 57, in which engage two endless cables, 58 and 58^a, which are guided by sheaves 59 on the bearing block 37 and by sheaves 60 and 60^x mounted on two posts 61, 62 respectively, which posts may be fixed in the ground a distance of from one hundred to two hundred feet apart, or farther yet for trains to be run fast while coaling. The straight parallel runs 58^b of said cables are spaced about ten or twelve inches apart and are at a certain point connected by a yoke 63, (see Fig. 12 and other views) which has a sliding motion

on the cables limited by fixed collars 65 and resisted by springs 64, which springs may either be fixed to the cables and stretched, as in Figs. 1 and 2, or may be compressed between the yoke and the collars 65, as in Fig. 12, in which modified form collars 65^x are to prevent undue rebounding of the yoke on the cables when it is suddenly released from the arm 66 of the tender. The yielding of said springs is to prevent a too sharp jerk on the cables and the tender when the arm of the latter engages the yoke.

It will be observed in Fig. 2 that the lower end of the side track is provided with a buffer 67 for stopping the carriage, and that from said buffer to the point 3^{xx} the track is inclined away from the buffer, so that the carriage has a tendency to start in the direction the train moves, especially so after the carriage is loaded with coal. To prevent said tendency from starting the carriage prematurely an automatic device is provided for locking and unlocking the carriage. Such locking device is shown in Fig. 2 in its simplest form, and in Figs. 7, 8, 9 and 11 as further improved. In said views 68 is a stationary post on which is pivotally mounted at 69 a two-tined fork 70, between whose normally upstanding tines the cable 42^a moves and is provided with the catch or dog 52, which has a hook 52^a engaging the stud 53 of the carriage, a body portion fixed on the cable, and a tail portion with two lateral arms 52^b, which latter when the carriage returns to the buffer engage the fork and, as in Fig. 2, raise it from the inclined to the vertical position; that is, from resting on the lug 71 to pressing or stopping against the lug 72. In the latter position the fork engages the stud 53, the way shown in Fig. 8, and prevents premature starting of the carriage, because any pressure which the stud 53 exerts against the fork tends to turn the fork at 52^b as a fulcrum, and such turning is prevented by the stationary fulcrum or pivot 69 and the resistance of the cable 42^a, since said cable can not that easily turn the spiral cone and all other mechanism connected therewith; but when the arm 66 of the train takes hold of the yoke 63 and thus by the spiral cone operates the cable 42^a, the latter takes the dog 52, fulcrum 52^b and stud 53 along, thereby inclining the fork so that the stud 53 passes over it, as shown in Figs. 2 and 9, leaving the style of fork in Fig. 2 resting on the lug 71, ready to engage the dog and stud when the carriage returns. In the modification shown in Figs. 7, 8, 9 and 11 the fork does not remain inclined, but as soon as the stud 53 has passed it, it is, by a weight 73, raised to vertical position, stopping against a lug 74 on the post; and each tine has its end portion pivoted at 75 and normally held against a supporting projection 76 by a spring 77, so that when the car-

riage returns the end portions of the tines will yield and let the stud 53 pass over them, as shown in Fig. 11, whereupon the springs will raise the tine portions, and the tines will serve the same as if they had no joints 73, as already described about Fig. 2.

As best shown in Fig. 3, if the car or tender 29^x is too low to reach up to the fork 23, a post 78 may be employed, and on said post the arm 25 is pivoted at 79 to swing upward from a support 80, so as to allow for the increasing height of the side track above the main track.

From the foregoing description of the structure and the functions and operations of the various parts and mechanisms it will be seen that the tender, or car, as the case may be, 29^x, when in motion in the direction of the arrow 81 in Fig. 1, first engages the yoke 63 and while compressing the springs 64 acts on the spiral cone to unlock the carriage, and while the carriage starts of its own weight down the short incline of the side track, the arm 66 becomes more effective on the yoke and by rotating the spiral cone causes the carriage to move faster and faster as the cable 43^x approaches the larger end of the cone; and at the time the carriage attains the same speed as the car the arm 25 trips the dumping device 10 and in a moment or two said device is emptied and the carriage is separated from the car by the laterally diverging track portion 3^x; at the same time the yoke 63 is removed from the arm 66 by passing partly around the large cable sheave 60^x. The carriage being thus set free from the train will soon be stopped by the inclined track and by the cable which may be permanently attached to it, and will then return by its own weight down the inclined track until it hits the buffer 67 and is locked again, as described, and filled for the next trip.

Among the several modifications falling within the scope and spirit of my invention it is obvious that a buffer (not shown) may be provided at the upper end of the side track, to stop the momentum of the carriage, which may move farther than the cable actually moves it, as hook 52^a of the dog is open for the stud 53 to pass out of it and return into it again when the carriage returns. The last mentioned action would however take place only if the train is run at a considerable speed. It is, however, intended that trains should run but between ten and twenty miles per hour while passing this coaling device, as such reduced speed is more safe and will answer the purpose of the invention.

What I claim is:

1. The combination with a main track and a car arranged to move thereon and provided with two lateral actuating arms, of an inclined and at its highest end laterally diverging side track near one side of the

- main track, a carriage movable on the side track and having a pivotally mounted goods-delivering dumping device, a self-locking trip holding the dumping device in normal position, means connected with the carriage for one of the actuating arms to engage and at a gradually increasing speed start the carriage before the car overtakes it; said trip being positioned to be engaged by the second actuating arm on the car when the car has got into position for receiving the goods from the carriage.
2. The combination with a main track and a car arranged to move thereon and provided with two lateral actuating arms, of an inclined and at its highest end laterally diverging side track near the main track, a carriage movable on the side track and having a pivotally mounted dumping device, a self-locking trip holding the dumping device in normal position, means connected with the carriage for one of the actuating arms to engage and at a gradually increased speed start the carriage before the car overtakes it; said trip being positioned for engagement by the second actuating arm on the car when the car has got into position for receiving the goods from the carriage; said dumping device arranged to be dumped by the weight of its contents, means on the carriage for returning the dumping device automatically to normal position after it is emptied, and means on the car arranged to automatically engage the dumping device and prevent its return until it is fully emptied.
3. In a device of the class described, the combination of a main track and an inclined side track adjacent thereto, a goods-delivering carriage movable on the side track and having a dumping device and a trip holding the same ready for dumping, a car movable on the main track and having an actuating arm arranged to act on the trip and dump the contents of the dumping device into the car, said arm having a vertical movement to allow the carriage to rise and fall with the incline of the side track, and means on the carriage to engage said arm and cause it to so remain in active position or relation to the trip.
4. The combination with a main track and a car arranged to move thereon and provided with two lateral actuating arms, of an inclined and at its highest end laterally diverging side track near the main track, a carriage movable on the side track and having a pivotally mounted dumping device, a self-locking trip holding the dumping device in normal position, means connected with the carriage for one of the actuating arms to engage and at a gradually increasing speed start the carriage before the car overtakes it; said trip being positioned for engagement by the second actuating arm on the car when the car has got into position for receiving the goods from the dumping device; said carriage and the means by which the moving car operates it being returnable to normal position by the weight of the carriage and the inclined position of the side track, and a cushioned buffer for stopping the carriage at its return to normal position.
5. The combination with a main track and a car arranged to move thereon and provided with two lateral actuating arms, of an inclined and at its highest end laterally diverging side track near the main track, a carriage movable on the side track and having a pivotally mounted dumping device, a self-locking trip holding the dumping device in normal position, means connected with the carriage for one of the actuating arms to engage and at a gradually increased speed start the carriage before the car overtakes it; said trip being positioned for engagement by the other actuating arm on the car when the car has got into position for receiving the goods from the dumping device; said carriage and the means by which the moving car operates it being returnable to normal position by the weight of the carriage and the inclined position of the side track, cushioned means for stopping the carriage at its return, and automatically acting means for locking the carriage in the returned position.
6. In a device of the class described, the combination with an inclined track having a buffer at its lower end, a carriage movable on the track and adapted to run by its own weight down the track against the buffer, an endless operating cable arranged to draw the carriage up the incline, driving means for moving the cable, and means for disengaging the cable from the driving means when the carriage is to return down the incline, locking means automatically engaging and locking the carriage in the returned position; said locking means being partly resilient to avoid shock by rebounding of the carriage from the buffer.
7. The combination with a main track and a car movable thereon and provided with two lateral actuating arms, an inclined and at its highest end laterally diverging side track, a carriage movable on the side track and having a pivotally mounted device for carrying and dumping goods into the car on the main track while said car is in motion; a stationary frame intermediate the ends of the side track, a spiral grooved cone mounted in said frame and having one or more peripheral grooves about its largest end, one or more endless cables engaging in said groove, or grooves, to rotate the cone, posts fixed near the main track a predetermined distance away in opposite directions from the frame, sheaves on said posts, and sheaves

- on said frame for guiding said cable, or cables, resilient means carried by said cable, or cables, for one of the actuating arms on the car to engage; an endless cable attached to the carriage and taken one or more turns about the cone, posts fixed some distance away from each side of the cone, sheaves on said posts and sheaves on the stationary frame for guiding the said cable, and a tripping device on the carriage for tripping the dumping device, said tripping device being arranged for operation by the other actuating arm on the car when the latter has reached a position alongside the carriage.
8. In a device of the kind described, a stationary frame, a spiral-grooved cone mounted to rotate therein, rods parallel to the axis of the cone, grooved sheaves slideable on the rods, a slideable skeleton frame on the rods and engaging the sheaves to slide them; self-adjustable means on the sliding frame engaging the spiral groove of the cone to move the frame; two tracks, a driving car on one of the tracks, an endless guided cable operable by said car and engaging the large end of the cone to rotate it, a driven car on the other track, an endless guided cable attached to said driven car and guided by the sheaves on the rods and taken one or more turns about the spiral-grooved portion of the cone, whereby the driving car is able to start the driven car slowly and then increase its speed gradually, while the driving car is moving at a uniform speed, and the cable in the spiral groove is bound to remain in said groove.
9. In a device of the class described, a stationary frame, two tracks adjacent thereto, a spiral-grooved cone mounted in the frame, a car adapted to be moving on one of the tracks, an endless guided cable engageable by said car and engaging the large end of the cone to turn it, a car on the other track, an endless guided cable attached to it and taken one or more turns about the smaller part of the cone so as to receive a gradually increased motion from the first mentioned car, and a stretching device engaging the second cable to automatically compensate for the variation in diameter of the different parts of the cone.
10. In a device of the class described, the combination of an inclined track, a carriage movable thereon, a buffer at the lower end of the track, an endless guided cable having one run attached to the carriage, means occasionally engaging the cable and pulling the carriage up the incline and then disengaging the cable to let the carriage return to the buffer, means for retaining the carriage near the buffer, said retaining means comprising a horizontal stud or arm on the carriage, an element fixed on the cable and engaging said stud, said element having a downward extension with two oppositely

disposed lateral arms; a post fixed near the lower end of the track, a two-tined fork pivotally mounted on the post to stand normally with the tines upward and to swing from a vertical position to a position inclined or leaning toward the highest end of the track, means preventing the fork from leaning in the reverse direction, and means for holding the fork in ready position for locking engagement with the stud and the element on the cable.

11. In a device of the class described, the combination of an inclined track, a carriage movable thereon, a buffer at the lower end of the track, an endless guided cable having one run attached to the carriage, means occasionally engaging the cable and pulling the carriage up the incline and then disengaging the cable to let the carriage return to the buffer, means for retaining the carriage near the buffer, said retaining means comprising a horizontally disposed stud on the carriage, an element fixed on the cable and engaging said stud, said element having a downward extension with opposite horizontal arms; a post fixed near the lower end of the track, a two-tined fork pivotally mounted on the post to stand normally with the tines upward and to swing from a vertical position to a position inclined toward the highest end of the track, means preventing the leaning of the fork in the reverse direction, and means for holding the fork in ready position for locking engagement with the stud on the carriage and the element on the cable; and a stretching device engaging the cable and adapted to yield sufficiently to permit the fork to form an offset in the cable when fully engaged with the element thereon, and to permit some rebounding of the carriage when it strikes the buffer.

12. In a device of the class described, the combination of an inclined track, a carriage movable thereon, a buffer at the lower end of the track, an endless guided cable having one run attached to the carriage, means occasionally engaging the cable and pulling the carriage up the incline and then disengaging the cable to let the carriage return to the buffer, a portion of said track near the buffer being inclined in opposite direction to the main portion of the track; means for retaining the carriage near the buffer on said reverse incline, said retaining means comprising a horizontal stud on the carriage, an element fixed on the cable and engaging said stud, said element having a downward arm with oppositely disposed horizontal fingers; a post fixed near the lower end of the track, a two-tined upwardly pointing fork pivoted to the post and arranged to swing from a vertical position to a leaning position toward the highest end of the main track portion, means preventing the fork from leaning toward the

buffer end of the track, means for holding the fork automatically in ready position to engage the element on the cable and then the stud on the carriage; said fork tines having their end portions pivoted to the main parts of the tines, means on the tines for supporting the end portions in line with the main portions of the tines, and resilient means

for holding the end portions against said supporting means.

In testimony whereof I affix my signature, in presence of two witnesses.

GUST HALL.
